Primary Examiner — Karen E Kearney*Assistant Examiner* — Cary M Robinson(74) Attorney, Agent, or Firm — McClure, Qualey & Rodack, LLP(57) CLAIM

The ornamental design for a display screen or portion thereof with graphical user interface, as shown and described.

DESCRIPTION

FIG. 1 is a front view of a display screen or portion thereof with graphical user interface showing my new design; and, FIG. 2 is a front view of a second embodiment thereof. The broken lines showing of a display screen or portion thereof, and text form no part of the claimed design.

1 Claim, 2 Drawing Sheets(56)
